MECHANICAL PROJECTOR

Joseph E. Scally, St. Louis, Mo.

Application November 15, 1939, Serial No. 304,512

15 Claims.

(Cl. 124—6)

This invention relates to a mechanical projector of the type suitable for throwing baseballs.

An object of this invention is to provide a mechanical projector suitable for throwing projectiles such as baseballs, which is simple in construction and efficient and safe in operation.

A specific object is to provide novel releasing mechanism for releasing the projectile which will be positive in operation, and which will be effective to release the ball to give substantially the same trajectory in successive operations, but which can also be adjusted.

Other and specific objects will be apparent from the following detail description, taken in connection with the accompanying drawings.

Fig. 1 is an elevation showing the left side of a machine embodying this invention;

Fig. 2 is a vertical section approximately on line 2—2, Fig. 1, showing details of a feeding mechanism;

Fig. 3 is a horizontal section approximately on line 3—3, Fig. 1, also showing details of the feeding mechanism;

Fig. 4 is an elevation showing the right side of the machine;

Fig. 5 is a section on line 5—5, Fig. 4, showing details of a slide and its mounting of releasing mechanism;

Fig. 6 is a section on line 6—6, Fig. 4, showing details of the slide and its mounting;

Fig. 7 is a view along line 7—7, Fig. 4, showing details of the releasing mechanism;

Fig. 8 is a rear elevation;

Fig. 9 is a view approximately on line 9—9, Fig. 8;

Fig. 10 is a view approximately on line 10—10, Fig. 8;

Fig. 11 is a section on line 11—11, Fig. 10;

Fig. 12 is a horizontal section on line 12—12, Fig. 8; and

Figs. 13, 14, 15 and 16 are views showing the relationship of parts of the releasing mechanism at concentric points in the cycle of operation.

A wheel, cylinder or propeller 1 is mounted on a shaft 2 by which it is rotated. The wheel has a spiral track or guide 3 by which or along which a projectile or ball B is moved from the central portion of the wheel outwardly towards its periphery to a point on the periphery where it is caught and held by a gate 4, which is a part of releasing mechanism. Balls B are fed by automatic mechanism, shown in assembly in Fig. 1 and Fig. 8, and shown in detail in Figs. 2 and 3. Release mechanism, which includes the gate 4, is so arranged and constructed as to unlatch the

gate 4 and permit the ball to be projected by centrifugal force at a selected point of travel and on a particular revolution in a cycle of operation. For instance, the mechanism may be adapted to release the ball each 120th revolution. The release mechanism is shown on the near side of the device, Fig. 4, and on the right side of the device, Fig. 8, while its details are shown in Figs. 5, 6, 7, 9, 10 and 11, with Figs. 13 to 16 showing progressive points in a cycle of operation. The mechanism is arranged to release the ball at a point in the revolution of the wheel or propeller when it is near the bottom. The particular point at which it is released may be adjusted by means which include a swinging frame 5 that carries some elements of the release mechanism, and shown in Figs. 4, 8, 9 and 12.

The foregoing description gives an outline of a machine embodying this invention, which may be better understood by the following detail description.

The wheel or propeller 1 includes a circular plate 6 which is secured to a boss or hub 7 rigid with the shaft 2. A parallel plate 8 and a peripheral strip 9 form the housing for the wheel. The plate 8 has a circular opening 8a at its central portion by which the balls B may be fed to the wheel. The spiral 3 within the housing extends from the opening 8a about the shaft 2 to the gate 4 where a strip 10 brings the ball to an opening in the peripheral piece 9 at the gate 4.

It may now be understood that balls may be fed through the opening 8a to the interior of the housing of the wheel or propeller 1 and that when they travel a spiral path as defined by the strip 3 to an opening in the rim of the wheel where they are held on the terminal strip 10 by the gate 4 until released by mechanism at a proper point in the cycle of operation.

40 The shaft 2 is supported on horizontal members 11 which are a part of a frame which includes a base 12 and uprights 13. The device may be mounted as illustrated, or its base may be mounted on a swivel.

45 A guard 14 is secured to the frame and supported by radial members 15 having their inner ends secured to yokes 16, supported by the horizontal frame members 11.

The wheel 1 is driven through a pulley 17 keyed to the shaft 2 and a belt 18 by a motor 19 supported on the base 12.

The balls may be fed to the wheel by hand if desired, or they may be fed by automatic means as illustrated in the drawings and presently described. Communicating troughs 20 (Fig.

1), the lower one of which is curved to discharge the balls through the opening 8a (Figs. 2 and 3) and providing a magazine for the balls and a path for their discharge to the propeller. This discharge is controlled by a pair of spaced gates 21 and 22 arranged to be operated in sequence. The gates 21 and 22 are arranged to be lowered and raised into and out of the path of the balls and are operated alternately for example at 180° intervals with respect to each other in the operation of the cycle of the machine. The gates 21 and 22 are secured to the upper end of push rods 23 and 24. These rods are operated by cams 25 and 26 on a shaft 27, driven by a speed reducing mechanism 28 which is operated through a sprocket chain 29 from the shaft 2. The reducing mechanism 28 is such that it operates in synchronism with the ball releasing mechanism later to be described in detail. For instance, if the ball is to be released once in each 120 revolutions the shaft 27 will be so geared through the reducer 28 that it will operate on a ratio of 1 to 120 in relation to the shaft 2.

The release mechanism may now be described in detail. The gate 4 is secured to a shaft 30 by screws 31 while the shaft is journalled in ears 32 supported by a framework 34 fastened to the wheel 1 (see Fig. 7). A weight 35 is carried by the outer end of an arm 36 secured to the shaft 30. The shaft 30 also carries a dog 37 by which the gate 4 is held and released. A slide 38 is mounted in a guide 39 on the face of the plate 6 of the wheel 1. The outer end of the slide 38 has a member 40 to engage the dog 37. It may now be understood that as the slide 38 moves outwardly it engages the dog 37, holds the shaft 30 against rotation and thereby positions the gate 4 to retain the ball on the wheel until the slide 38 is moved inwardly so that the member 40 is out of engagement with the dog 37.

Mechanism is provided for moving the slide 38 inwardly at a certain point in the cycle of operation. This mechanism is mounted on the swinging frame 5 about the shaft 2 so that it may be adjusted in an arcuate path with the axis of the wheel 1 as its center. The frame includes a front upright 41, a bottom cross member 42 and brace members 43 at its front (Figs. 4 and 12). At its rear it has an upright member 44. The front and rear portions are secured together by a bottom lateral member 45 and lateral braces 46 (Fig. 12).

The slide 38 supports a dog 47 which is adapted to be engaged by the end of an arm 48 and also by the end of an arm 49 mounted radially on a timing member or disc 50. The arrangement is such that the end of the arm 48 is adapted to come into engagement with the dog 47 to move the slide 38 at one point in the cycle of operation. For example, the timing member or disc 50 may be driven in such a manner that the slide 38 will be moved by the arm 48 once in 120 revolutions of the wheel 1.

The rotation of the disc 50 is initiated by a gear 51 secured to the shaft 2 which, through an idler 52, drives a gear 53 secured to a shaft 54. The idler 52 is mounted in a cage or frame 55 on the front upright 41 of the frame 5 and the shaft 54 has its ends journalled respectively in the frame members 43 and 44.

The shaft 54 carries a gear 56 meshing with and driving a gear 57 on a shaft 58, which also carries the disc or timing member 50.

The arrangement of the gears is such that 75

the shaft 54 is driven at the same rate as the shaft 2 but the gears 56 and 57 have a different number of teeth so that the shaft 58 and therefore the timing member or disc 50 is driven at either a slightly less or a slightly greater speed than the wheel 1. As shown on the drawings (Figs. 13 to 16) the disc 50 is driven faster than the wheel 1 or shaft 2. For example, the gear 56 may have 121 teeth while the gear 57 may have 120 teeth; thus the timing disc 50 will rotate 121 revolutions while the wheel 1 rotates 120 revolutions. Now it may be understood that the arm 48 will come into engaging position under such a specific arrangement of gears once in each 120 revolutions of the wheel 1.

The operation of the release mechanism may be explained by reference to Figs. 13 to 16. Under the example given in which the cycle comprises 120 revolutions, the position of the mechanism at the 119th revolution of the shaft 2 will be as shown in Fig. 13. It will be seen there that the dog 47 and the arm 48 do not quite contact. But in Fig. 14 at about the end of the 120 revolutions the end of the arm 48 is about to contact the dog 47 while shortly thereafter, as shown in Fig. 15, this contact has been made and the slide 38 has been moved to release the latch 40 from the dog 37, integral with the gate 4, so that the gate is free to swing and release the ball B.

Fig. 16 illustrates the condition of the apparatus which may occur after the release of the gate and the ball. The mechanism is in condition as it may be at the end of the first revolution of a cycle. The gate has assumed a position in which it is not caught and held by contact of the member 40 and the dog 37. This may happen or may not happen depending on chance. But in the position as shown in Fig. 16 the gate 4 will not hold a ball and this condition requires correction, which is accomplished by the arm 49 which is 90° removed from the arm 48 and which will come into engagement with the dog 47 on the 30th revolution (assuming the example as indicated above) or at the end of a 90° period. When the arm 49 moves the slide 38 from the position shown in Fig. 16 the weight 35 by its centrifugal force will rotate the gate 4 in a counterclockwise direction until the weight extends radially and the dog 37 is positioned on the member 40. When the ball B is then introduced it contacts the gate and moves it and its associated parts to the position shown in Fig. 13.

Since the frame 5 which carries with it and supports the timing disc 50 may be adjusted accurately the ball may be released at any predetermined position of the wheel within limits. Means for adjusting the position of the frame 5, and therefore the point at which the ball may be released, is illustrated in Figs. 4, 8 and 12. An adjustment board 59 is supported by a frame 60 secured to the cross member 11 and the base 12 of the principal frame. This board 59 has arcuate slots 61 through which extend pins 62 carried by the frame member 42 of the frame 5. Nuts 63 on the pins 62 serve to clamp the swinging frame in any adjusted position on the board 59.

Various changes may be made in the details of construction, within the scope of the appended claims, without departing from the spirit of this invention, and parts of the invention may be used to advantage without the whole.

I claim:

1. In game apparatus of the class described having a propeller and means for continuously rotating the propeller at a substantially constant speed, holding and releasing means for a projectile comprising a gate hinged on the extremity of the propeller for retaining a projectile, a reciprocating latch mounted on the propeller and engaging the gate, and timing mechanism for moving the latch automatically to release the gate at a predetermined point in a circle of rotation of the propeller during a certain rotation in each cycle which includes a predetermined plurality of rotations of the propeller.

2. In game apparatus of the class described having a propeller, means for continuously rotating the propeller at a substantially constant speed and a spiral guide on the propeller adapted to receive a projectile near the axis of the propeller and leading to a point on the extremity thereof, holding and releasing means for the projectile comprising a gate hinged on the extremity of the propeller for retaining the projectile at said point, a reciprocating latch mounted on the propeller and engaging the gate, and timing mechanism for moving the latch automatically to release the gate at a predetermined point in a circle of rotation of the propeller during a certain rotation in each cycle which includes a predetermined plurality of rotations of the propeller.

3. In game apparatus of the class described having a propeller, means for continuously rotating the propeller at a substantially constant speed and a spiral guide on the propeller adapted to receive a projectile near the axis of the propeller and leading to a point on the extremity of the propeller, holding and releasing means for the projectile comprising a gate on the extremity of the propeller for retaining the projectile at said point, a reciprocating latch mounted on the propeller and engaging the gate, and timing mechanism for moving the latch automatically to release the gate at a predetermined point in a circle of rotation of the propeller during a certain rotation in each cycle which includes a predetermined plurality of rotations of the propeller, and automatic feeding means for introducing a projectile to said guide during each of said cycles.

4. In a mechanical projector having a rotary propeller, holding and releasing means for a projectile comprising a gate, a shaft to which the gate is secured mounted on the extremity of the propeller, a dog on the outer end of the shaft, a slide mounted on the propeller for engaging the dog, and means supported independently of the propeller for engaging and moving the slide to release the gate.

5. In game apparatus of the class described having a rotary propeller adapted to be continuously rotated at a constant speed, holding and releasing means for a projectile comprising a gate hinged on the extremity of the propeller, a latch for the gate carried by the propeller, timing mechanism supported independently of the propeller but driven with the propeller for moving the latch automatically to release the gate at a predetermined point in a circle of rotation of the propeller during a certain rotation in each cycle which includes a predetermined plurality of rotations of the propeller.

6. In game apparatus of the class described having a rotary propeller, holding and releasing means for a projectile comprising a gate hinged

on an extremity of the propeller, a latch for the gate carried by the propeller, timing mechanism for moving the latch, and a frame supporting said mechanism independently of the propeller and movable to a plurality of positions whereby said mechanism may move said latch to release the projectile at any of a plurality of selected points in the circle of rotation of the propeller.

10 7. In game apparatus of the class described having a rotary propeller, holding and releasing means for a projectile comprising a gate hinged on an extremity of the propeller, a latch for the gate carried by the propeller, timing mechanism for moving the latch, and a frame supporting said mechanism independently of the propeller and mounted for movement in an arc about the axis of the propeller to any of a plurality of positions whereby said mechanism may move said latch to release the projectile at any of a plurality of selected points in the circle of rotation of the propeller.

20 8. In game apparatus of the class described having a rotary propeller adapted to be continuously rotated at a constant speed, holding and releasing means for a projectile comprising a gate hinged on the extremity of the propeller for retaining a projectile, a latch for the gate slidably mounted on the propeller, timing mechanism for moving the latch to release the gate at a predetermined point in a circle of rotation of the propeller during a certain rotation in each cycle which includes a predetermined plurality of rotations of the propeller, and devices for adjusting the position of said mechanism to change at will within limits a point in the circle of rotation at which the latch releases the gate.

25 9. In a mechanical projector having a rotary propeller, holding and releasing means for a projectile comprising a shaft mounted on an extremity of the propeller, a gate secured to the shaft, a counterweight secured to the shaft and positioned and adapted under the influence of centrifugal force to place the gate in a position to engage the projectile, and a latch for the gate to limit movement of the gate under the influence of the projectile's centrifugal force.

30 10. In a mechanical projector having a rotary propeller, holding and releasing means for a projectile comprising a shaft mounted on an extremity of the propeller, a gate secured to the shaft, a counterweight secured to the shaft positioned and adapted under the influence of centrifugal force to place the gate in a position to engage the projectile, a latch for the gate to limit movement of the gate under the influence of the projectile's centrifugal force, and means adapted to move the latch to release the gate twice during each cycle which includes a predetermined plurality of rotations of the propeller and so arranged as to release the projectile at a particular point in the circle of rotation and during a predetermined rotation in the cycle and then to release the latch to permit the counterweight to correct the position of the gate.

35 11. In a mechanical projector having a rotary propeller, holding and releasing means for a projectile comprising a shaft mounted on an extremity of the propeller, a gate secured to the shaft, a counterweight integral with the shaft and the gate, a dog on an outer end of the shaft, a slide mounted on the propeller for engaging the dog, and means adapted to move the slide to release the gate twice during each cycle which includes a predetermined plurality of rotations of

the propeller and so arranged as to release the projectile at a particular point in the circle of rotation and during a predetermined rotation in the cycle and then to release the latch to permit the counterweight to correct the position of the gate.

12. In a mechanical projector having a rotary propeller, holding and releasing means for a projectile comprising a gate, a slide on the propeller for securing and releasing the gate, a rotary shaft supported independently of the propeller, an arm carried by the shaft and arranged to contact and move the slide to release the gate, and driving means for said shaft connected with the propeller so constructed and arranged as to cause said shaft to be driven at near the same but a different rate as the propeller whereby the arm moves the latch to release the gate at a predetermined point in a circle of rotation of the propeller during a certain rotation in each cycle which includes a predetermined plurality of rotations of the propeller.

13. In a mechanical projector having a rotary propeller, holding and releasing means for a projectile comprising a gate, a slide on the propeller for securing and releasing the gate, a rotary shaft supported independently of the propeller, an arm carried by the shaft and arranged to contact and move the slide to release the gate, driving means for said shaft connected with the propeller so constructed and arranged as to cause said shaft to be driven at near the same but a different rate as the propeller whereby the arm moves the latch to release the gate at a predetermined point in a circle of rotation of the propeller during a certain rotation in each cycle which includes a predetermined plurality of rotations of the propeller, and a second arm on said shaft also adapted to move the slide but at a second point in the cycle.

14. In a mechanical projector having a rotary propeller, holding and releasing means for a pro-

jectile comprising a gate, a slide on the propeller for securing and releasing the gate, a shaft supported independently of the propeller, an arm carried by the shaft and arranged to contact and move the slide to release the gate, driving means for said shaft connected with the propeller so constructed and arranged as to cause said shaft to be driven at near the same but a different rate as the propeller whereby the arm moves the latch to release the gate at a predetermined point in a circle of rotation of the propeller during a certain rotation in each cycle which includes a predetermined plurality of rotations of the propeller, and a frame supporting said shaft and mounted for movement in an arc about the axis of the propeller to a plurality of positions in such a manner as to release the projectile at any of a plurality of selected points in the circle of rotation of the propeller.

15. In a mechanical projector having a rotary propeller, holding and releasing means for a projectile comprising a gate, a slide on the propeller for securing and releasing the gate, a shaft supported independently of the propeller, an arm carried by the shaft and arranged to contact and move the slide to release the gate, gearing connecting the propeller and the shaft so constructed and arranged as to cause said shaft to be driven at near the same but a different rate as the propeller whereby the arm moves the latch to release the gate at a predetermined point in the circle of rotation of the propeller during a certain rotation in each cycle which includes a predetermined plurality of rotations of the propeller, and a frame supporting said shaft and said gearing mounted for movement in an arc about the axis of the propeller to a plurality of positions in such a manner as to release the projectile at any of a plurality of selected points in the circle of rotation of the propeller.

JOSEPH E. SCALLY.
